UNITED STATES PATENT OFFICE.

ALBERT AEBI AND FRANÇOIS JEANTET, OF GENEVA, SWITZERLAND.

PINCH SUPPORT FOR GARMENTS (WOVEN OR KNITTED GOODS).

Application filed October 23, 1922. Serial No. 596,466.

To all whom it may concern:

Be it known that we, ALBERT AEBI and FRANÇOIS JEANTET, citizens of Switzerland and France, respectively, residing at Geneva, 5 Canton of Geneva, in the Confederation of Switzerland, have invented certain new and useful Improvements in Pinch Supports for Garments (Woven or Knitted Goods), of which the following is a specification.

10 The object of the invention is an improvement in pinch-supports for garments, particularly adapted to suspend a pair of drawers to the waist-band of the pantaloons, but which may also be used for supporting other 15 woven or knitted garments either for ladies or gentlemen, the pinch holding the stuff tightly without risk of damaging it.

The essential feature of the pinch-support consists in the combination of a member, 20 formed so that it may be hooked onto the rim of a garment, is provided with a loop whose edges are rounded off, a first lever which pivots on said member, and a second lever pivoting on the first lever and having a knob 25 whose head is rounded off and which is adapted to press the stuff into said loop with smooth edges, the pivot of the second lever being arranged with regard to the pivot of said first lever in such a manner that the 30 knob may engage within the loop and that when thereafter the first lever is pressed onto the second lever the cloth which covers the knob is pinched between the latter and the loop.

35 The attached drawing shows on an enlarged scale, by way of example, a working form of the invention.

Fig. 1 is a front view and

Fig. 2 is a side view of the open pincher.

40 Fig. 3 is a side view, partly in section, of the pincher in position to engage the stuff into the loop.

Fig. 4 is a side view, partly in section, of the pinch-support when closed, with a piece 45 of cloth pressed between the button and the edges of the loop.

50 *a* is a punched metal member provided with a hook *b* adapted to be hooked for instance onto the waist-band of a pair of pants, and with a loop *c* whose edges are bent round by

the punch to form a roll within which the stuff or cloth may be engaged without being damaged.

The member *a* has also two ears *d*, in which a first lever *f* may swivel on a metal tube *e* with riveted ends. The lever *f* is also provided with two ears *g* in which by means of the metal tube *h* with riveted ends a second lever *i* carrying a knob *k* may swivel. The knob *k* is covered with the stuff or cloth *x*, 60 for instance the waist-band of a pair of drawers which then is pressed into the loop *c* of the member *a* as shown in Fig. 3.

When the first lever *f* is pressed down onto the second lever *i*, the latter is pushed downwards and the stuff *x* is pinched between the knob *k* and the edge of the loop *c*.

The pinch-support may be constructed and suitably ornamented in different ways.

In the working form as represented it 70 consists of three pinched pieces and two small tubes which constitute hinges.

Instead of a hook *b* a metal loop adapted to be attached to the garters, braces or the like may be provided for.

Having now described our invention and the manner in which it may be performed, we declare that what we claim is:—

1. A garment supporting clasp comprising a loop carrying member, a loop, having bent 80 edges forming a roll, carried by said member, a two piece toggle member cooperating with the loop carrying member, one of the toggle pieces being an actuating member, the other toggle piece being an actuated member and having a shank portion curved to conform to the curvature of the loop, and a knob carried by the shank portion, whereby fabric can be pressed into said loop, by said knob and held therein, wherein the loop carrying 85 member has a curved portion for affording a limited elasticity to the clip between the knot and the loop.

2. A garment supporting clasp comprising, a loop carrying member, a loop, having bent edges forming a roll, carried by said member, a two piece toggle member cooperating with the loop carrying member, one of the toggle pieces being an actuating member, the other toggle piece being an actuated 95 100

member and having a shank portion curved to conform to the curvature of the loop, and a knob carried by the shank portion, whereby fabric can be pressed into said loop, by said 5 knob and held therein, wherein the loop carrying member is of stamped metal, and has pivoting ears, the actuating toggle member being pivoted in said ears, the actuated member being pivoted to the actuating member

eccentrically to the pivot of the actuating 10 member.

In testimony whereof we have affixed our signatures in presence of two witnesses.

ALBERT AEBI.
FRANÇOIS JEANTET.
